UNITED STATES PATENT OFFICE.

BENJAMIN GRIFFITH, JR., OF EVANSTON, ILLINOIS, ASSIGNOR OF ONE-HALF TO GUSTAVE ALBERT JOHNSON, OF EVANSTON, ILLINOIS.

WHEEL-MOUNTING DEVICE.

Application filed September 17, 1923. Serial No. 663,287.

To all whom it may concern:

Be it known that I, BENJAMIN GRIFFITH, Jr., a citizen of the United States, residing at Evanston, in the county of Cook and 5 State of Illinois, have invented certain new and useful Improvements in Wheel-Mounting Devices, of which the following is a specification.

My invention relates to wheel mounting 10 devices of the type for use in connection with disk wheels, and it is the object of my invention to provide a new and improved arrangement of parts which shall act to guide and support such a wheel into proper 15 position with respect to the hub already in position upon the axle.

It is one of the objects of my invention to improve devices of this type in sundry 20 details, hereinafter pointed out. The preferred means by which I have accomplished 25 my objects are illustrated in the drawings and are hereinafter specifically described. That which I believe to be new and desire to cover by this application is set forth in the claims.

In the drawings,

Fig. 1 is a view showing the preferred 30 form of my device in position on a hub cap for the mounting of a disk wheel, a fragmentary portion of which wheel is shown in section in said figure.

Fig. 2 is an enlarged detail view, partly 35 in section, and showing a changed position of certain of the parts.

Fig. 3 is a vertical cross section taken on line 3—3 of Fig. 1.

Fig. 4. is a vertical cross section taken substantially on line 4—4 of Fig. 1.

Fig. 5 is a cross sectional view taken at 40 line 5—5 of Fig 4.

Fig. 6 is a view similar to Fig. 1, but showing a modified form of construction.

Fig. 7 is a fragmentary top plan view of the device as shown in Fig. 1.

Fig. 8 is a vertical cross section taken substantially at line 8—8 of Fig. 1, and

Fig. 9 is a perspective view of one of the brackets forming a part of the device of Fig. 7.

Referring now to Figs. 1 to 5 of the drawings in which corresponding parts are indicated by the same reference characters, it will be seen that my device is in the form of a ring 15 which is of a size to pass read-

ily into position upon the hub cap 16 of an 55 automobile over the enlarged outer end thereof, an arm being connected with the ring in position to extend outwardly beyond the end of the hub as shown in Figs. 1 and 2, being preferably in inclined position 60 when so extended and being preferably pivotally connected with the ring 15.

In the construction shown, the arm comprises a bar 17 which is pivotally connected by means of a bolt 18 between the 65 upwardly directed end portions of the ring 15, which in the construction shown is in the form of a steel band bent into shape, as is best shown in Fig. 4. The arm comprises further two bars 19 which are connected with the bar 17 near the outer end of the bar and extend toward the ring 15 in diverging position so as to be in contact with the ring 15 at opposite sides thereof when the arm is in operative position, as 70 is shown in Figs. 1 and 4. The bars 19 are connected together at an intermediate point by a cross brace 20 which is provided at its middle point with a loop 21 engaging the bar 17, the brace 20 serving to reinforce the 75 diverging bars 19 and 19 with respect to each other. A fourth bar 22 is rigidly mounted upon the bar 17 in diverging position with respect thereto, being in position to engage the outer end of the hub cap 16 80 for supporting the arm comprising the bars 17 and 19 in the desired inclined position beyond the end of the hub comprising the cap 16.

For holding the ring 15 against withdrawal from the hub cap 16, I have provided a lug 23 in the form of a block secured upon the bar 17 adjacent to the pivot bolt 18. As is clearly shown in Fig. 2, when the arm comprising the bar 17 is 90 in normal outwardly extended position, the block 23 stands in position opposite the inner face of the enlargement upon the end of hub cap 16, serving to prevent withdrawal of the ring 15 from the hub cap. 95 When it is desired to withdraw the device from the hub cap, it is only necessary that the arm be swung about the pivot bolt 18 into raised position, as indicated by dotted lines in Fig. 2, causing the lug 23 to clear 100 the enlargement or head of the hub cap for permitting ready withdrawal of the ring 15.

Referring now to Figs. 6 to 9 inclusive,

in which the modified form of construction is illustrated, corresponding parts are indicated by the same reference characters. In this construction, the hub comprises a cap 24 which is not provided with an enlarged outer end, wherefore it is necessary to provide some other expedient for preventing the withdrawal of the device from the hub. In the construction here shown, the clamping member engaging the hub is also in the form of a split ring 25 which, in the construction shown, is formed of band steel with its end portions turned outwardly into parallel position. In this construction, a bar 26 is substituted for the bar 17, the bar 26 being connected with the clamping member or ring 25 by means of a bolt 27 and brackets 28 and 29, which in the construction shown are riveted upon the end of the bar 26. As is shown in Fig. 7, the turned ends of the band forming the ring 25 stand in spaced relation so as to be free to move toward each other for tightening the ring upon the hub cap 24. As is best shown in Fig. 9, the inner faces of the brackets 28 and 29 are provided with cams 30 so arranged that when the bar 26 is turned into alignment with the ring 25, the ring is adapted to expand so as to be loose upon the hub cap 24, the arrangement being such, however, that when the bar 26 is turned downwardly into operative position, as shown in Fig. 6, the cams 30 operating upon the outer faces of the turned ends of the band forming the ring 25 cause the band to tighten upon the hub cap 24 so as to prevent withdrawal of the ring or clamping member 25 from the hub.

With my improved device comprising the clamping member and the arm, tightened upon a hub cap, as shown in either Fig. 1 or Fig. 6, a disk wheel 31 (only a portion of the disk of which is shown) is lifted into position upon the outer end of the arm and is slid toward the right in either of such figures toward the flange 32 of the hub upon which the disk is to be secured by means of bolts 33, or by any other suitable securing means. The position of the arm 50 is such with respect to the flange 32 that the wheel is normally supported in position thereon so as to slide readily into place upon the hub, the bars 19 being preferably in such position as to center the wheel horizontally 55 while the bar 17 centers the wheel vertically with respect to the hub.

While I prefer to employ one of the forms of device as shown in my drawings, it will be understood that I do not wish to restrict myself to the use of such forms, except so far as such forms are specifically claimed, inasmuch as it is evident that various changes might be made in the construction without departing from the spirit of my invention.

I claim:

1. A device for mounting a disk wheel upon its hub in position on an axle, comprising a clamping member adapted to be releasably supported by the hub, and an arm connected with the clamping member and supported in extended position for directing the wheel to its working position.

2. A device for mounting a disk wheel upon its hub in position on an axle, comprising a clamping member adapted to be releasably supported by the hub, and an arm connected with the clamping member and supported in inclined position beyond the end of the hub with its inner end at a level for directing the wheel to its working position.

3. A device for mounting a disk wheel upon its hub in position on an axle, comprising a clamping member adapted to be releasably supported by the hub by engagement with the hub cap, and an arm connected with the clamping member and engaging the hub cap for directing the wheel to its working position.

4. A device for mounting a disk wheel upon a hub in position on an axle, comprising a clamping member adapted to be releasably supported by the hub, and an arm pivotally connected with the clamping member and held by engagement with the hub cap in inclined position for directing the wheel to its working position.

5. A device for mounting a disk wheel upon its hub in position on an axle, comprising a clamping member adapted to be releasably supported by the hub, and an arm connected with the clamping member and supported in extended position beyond the end of the hub for directing the wheel to its working position, said arm comprising means for guiding the wheel both horizontally and vertically with respect to the position of the hub.

6. A device for mounting a disk wheel upon its hub in position on an axle, comprising a clamping member adapted to be mounted upon the hub, an arm connected with the clamping member for directing the wheel to its working position, and clamping means adapted upon the movement of the arm into operative position to hold the clamping member in position with respect to the hub.

7. A device for mounting a disk wheel upon its hub in position on an axle, comprising a clamping member adapted to be mounted upon the hub, an arm pivotally connected with said clamping member so as to be capable of being swung into inclined position beyond the end of the hub, and clamping means adapted upon the movement of the arm into operative position to hold the clamping member in position on the hub whereby the arm may direct the wheel to its working position on the hub.

8. A device for mounting a disk wheel upon its hub in position on an axle, comprising a clamping member adapted to be releasably secured upon the hub, an arm 5 pivotally connected with said clamping member, and a bearing on said arm adapted by engagement with the end portion of the hub to hold said arm in position for directing the wheel to its working position on the hub. 10
9. A device for mounting a disk wheel upon its hub in position on an axle, comprising a clamping member adapted to be mounted upon the hub, means for holding 15 the clamping member against withdrawal from the hub, and an arm connected with said clamping member and supported in position for directing the wheel to its working position on the hub. 20
10. A device for mounting a disk wheel upon its hub in position on an axle, comprising a clamping member adapted to be mounted upon the hub, an arm pivotally connected with said clamping member, 25 means carried by the arm adapted when the arm is in operative position to prevent withdrawal of the clamping member from the end of the hub, and means for supporting said arm in position for directing the wheel to 30 its working position on the hub.
11. A device for mounting a disk wheel upon its hub in position on an axle, comprising a ring adapted to be mounted upon the hub, an arm connected with said ring, 35 means serving when the arm is in operative position to prevent withdrawal of the ring from the hub, and means for supporting said arm in inclined position beyond the end of the hub for directing the wheel to 40 its working position on the hub.
12. A device for mounting a disk wheel upon its hub in position on an axle, comprising a ring adapted to be mounted upon the hub, an arm pivotally connected with 45 said ring, means rendered operative by the movement of the arm into normal inclined position for preventing withdrawal of the ring from the hub, and means for supporting said arm in operative position for directing the wheel to its working position on the hub. 50
13. A device for mounting a disk wheel upon its hub in position on an axle, comprising a ring adapted to be mounted upon the hub, an arm pivotally connected with 55 said ring, a lug carried by the arm in position to engage the end of the hub cap for preventing withdrawal of the ring therefrom when the arm is moved into operative 60 position, and means for supporting said arm in operative position for directing the wheel to its working position on the hub. 65
14. A device for mounting a disk wheel upon its hub in position on an axle, comprising a ring adapted to be mounted upon 70 the hub, an arm comprising a plurality of diverging bars held in spaced relation substantially corresponding to the size of the opening in the disk, said arm being pivotally connected with said ring, means for releasably securing said ring on said hub, and means for supporting said arm in inclined position beyond the end of the hub for directing the wheel to its working position on the hub. 75
15. A device for mounting a disk wheel upon its hub in position on an axle, comprising a ring adapted to be mounted upon the hub, an arm comprising a plurality of diverging bars held in spaced relation substantially corresponding to the size of the opening in the disk, said arm being pivotally connected with said ring, means for releasably securing said ring on said hub, and means carried by the arm adapted by engagement with the end portion of the hub to support said arm in inclined position beyond the end of the hub for directing the wheel to its working position on the hub. 80
16. A device for mounting a disk wheel upon its hub in position on an axle, comprising a ring adapted to be mounted upon the hub, an arm comprising a plurality of diverging bars held in spaced relation substantially corresponding to the size of the opening in the disk, said arm being pivotally connected with said ring, means for releasably securing said ring on said hub, and means carried by the arm adapted by engagement with the end portion of the hub to support said arm in inclined position beyond the end of the hub for directing the wheel to its working position on the hub. 85
17. A device for mounting a disk wheel upon its hub in position on an axle, comprising a ring adapted to be mounted upon the hub, a bar pivotally mounted on said ring, two additional bars mounted on said first named bar at a distance from the pivotal connection with the ring and diverging so as to engage the ring at opposite sides when the arm is swung to operative position, means for releasably securing said ring on said hub, and means for supporting said arm in extended position beyond the end of the hub for directing the wheel to its working position on the hub. 90
18. A device for mounting a disk wheel upon its hub in position on an axle, comprising a ring adapted to be mounted loosely over the enlarged end of the hub cap, an arm pivotally connected with said ring, a block carried by the arm adjacent to the pivotal point for engaging the enlarged end 100 of the hub cap when the arm is swung into operative position for preventing withdrawal of the ring from the cap, and means for supporting said arm in extended position beyond the outer end of the hub cap for 105

supporting the wheel and directing it to its working position on the hub.

19. A device for mounting a disk wheel upon its hub in position on an axle, comprising a ring adapted to be mounted upon the hub, an arm pivotally connected with said ring, cam means for tightening the ring upon the hub, and means for supporting the arm in extended position beyond the outer end of the hub for supporting the wheel and directing it to its working position on the hub.

20. A device for mounting a disk wheel upon its hub in position on an axle, comprising a ring adapted to be mounted upon the hub, an arm pivotally connected with said ring, cam means actuated by the movement of the arm into operative position for tightening the ring upon the hub, and means for supporting the arm in extended position beyond the outer end of the hub for supporting the wheel and directing it to its working position on the hub.

21. A device for mounting a disk wheel upon its hub in position on an axle, comprising a split ring adapted to be mounted upon the hub, means for tightening the ring upon

the hub, and an arm connected with the ring and supported in extended position beyond the end of the hub for directing the wheel to its working position on the hub.

22. A device for mounting a disk wheel upon its hub in position on an axle, comprising a split ring adapted to be mounted upon the hub, an arm pivotally mounted on said ring, means actuated by the movement of the arm into operative position for tightening the ring upon the hub, and means for supporting the arm in inclined position beyond the end of the hub for directing the wheel to its working position on the hub.

23. A device for mounting a disk wheel upon its hub in position on an axle, comprising a split ring adapted to be mounted upon the hub, an arm pivotally mounted on said ring, cam means actuated by the movement of the arm into operative position extended beyond the end of the hub for tightening the ring upon the hub, and means adapted by engagement with the hub for supporting the arm in operative position for supporting the wheel and directing it to its working position on the hub.

BENJAMIN GRIFFITH, JR.
